UNITED STATES PATENT OFFICE

169,000

OVERSHOE OR THE LIKE

Jacob Simon Kamborian, West Newton, Mass., assignor to Kamborian Products, Inc., Cambridge, Mass., a corporation of Massachusetts

Application January 3, 1952, Serial No. 17,911

Term of patent 14 years

(Cl. D7—4)

To all whom it may concern:

Be it known that I, Jacob S. Kamborian, a citizen of the United States of America, residing at 133 Forest Avenue in West Newton, county of Middlesex, and Commonwealth of Massachusetts, have invented a new, original, and ornamental Design for an Overshoe or the like, of which the following is a specification, reference being had to the accompanying drawings forming a part thereof.

Fig. 1 is a front perspective view of an overshoe, showing my new design;

Fig. 2 is a rear elevation of the overshoe;

Fig. 3 is a side elevational view of the overshoe, portions of the strap elements being broken away for convenience of illustration; and

Fig. 4 is a bottom plan view of the overshoe as shown in Fig. 3.

Both sides of the upper of the overshoe illustrated in the foregoing figures are substantially the same in appearance.

I claim:

The ornamental design for an overshoe or the like, substantially as shown and described.

JACOB SIMON KAMBORIAN.
